(57) **CLAIM**

I claim the ornamental design for glass lavatory of cast glass with an integral back splash, as shown and described.

DESCRIPTION

FIG. 1 is a top front perspective view of the glass lavatory of cast glass with an integral black splash showing my new design.

FIG. 2 is a front elevation view thereof.

FIG. 3 is a rear elevation view thereof.

FIG. 4 is a left side elevation thereof.

FIG. 5 is a right side elevation thereof.

FIG. 6 is a top plan view thereof; and,

FIG. 7 is a bottom plan view thereof.
